UNITED STATES PATENT OFFICE

132,135

DESIGN FOR A TEXTILE FABRIC

William H. Rigney, La Fayette, R. I., assignor to A. Sterzelbach & Sons Co., New York, N. Y., a firm composed of Herbert Sterzelbach and Lester Sterzelbach

Application November 23, 1940, Serial No. 96,754

Term of patent 7 years

To all whom it may concern:

Be it known that I, William H. Rigney, a citizen of the United States of America, residing in La Fayette, county of Washington, and State of Rhode Island, have invented a new, original, and ornamental Design for a Textile Fabric, of which the following is a specification, reference being had to the accompanying drawing, forming part thereof, wherein the figure of the drawing is a plan view of a textile fabric showing my new design.

I claim:

The ornamental design for a textile fabric, substantially as shown.

WILLIAM H. RIGNEY.
